UNITED STATES PATENT OFFICE.

MAX HERSKOVITZ, OF CHICAGO, ILLINOIS, ASSIGNOR TO PEERLESS LIGHT COMPANY, OF CHICAGO, ILLINOIS, A CORPORATION OF MAINE.

ELECTRIC CANDLE-SOCKET STRUCTURE.

Application filed November 10, 1920. Serial No. 423,026.

To all whom it may concern:

Be it known that I, MAX HERSKOVITZ, a citizen of the United States, residing at Chicago, in the county of Cook and State of Illinois, have invented a new and useful Improvement in Electric Candle-Socket Structures, of which the following is a specification.

The primary object of my invention is to provide a construction of electric candle-socket which may be economically manufactured, will be strong and durable and which will present an attractive appearance.

Referring to the accompanying drawings: Figure 1 is a view in elevation of a candle-socket structure constructed in accordance with my invention. Figure 2 is a similar view with certain parts thereof shown in section. Figure 2^a is a view in side elevation of the central portion of the candle-socket structure. Figures 3 and 4 are perspective views of the two parts forming the base member of the candle-socket. Figure 5 is a similar view of an insulating shell serving as a lining for the part shown in Fig. 4. Figure 6 is a view in elevation, partly sectional, of the base portion referred to, showing the parts illustrated in Figs. 3 and 4 in assembled position, with the insulating shell of Fig. 5 in place therein. Figure 7 is a sectional view taken at the irregular line 7—7 on Fig. 6 and viewed in the direction of the arrows; and Figure 8, an enlarged view in elevation of the lower end of the structure shown in Fig. 2^a, viewed from a position to show the binding posts of the switch device.

The candle-socket structure is formed with a supporting member comprising the section 8 shown in Fig. 3 and the section 9 shown in Fig. 4 forming a candle-cup. The section 9 is in the form of a socket having its upper end open, its lower end represented at 10 being shown as contracted at which it is adapted to be connected with any suitable support, as for example the rigid pipe shown at 11 and through which the electric current-conducting wires represented at 12 and 13 lead to the contacts of the structure hereinafter described, the pipe 11 being shown as a wall bracket. The member 8 is in the form of a disk having an upwardly and inwardly turned annular flange 14, the central part of the disk 8 being apertured as represented at 15 from which portion, a

cylindrical sleeve member 16 rises, the upper end of this sleeve member being contracted circumferentially to produce the reduced annular portion 17 and provide an annular shoulder 18, the members 8 and 9 being preferably of metal and both members of integral construction. The wall of the member 9 is slotted from its upper end part way to its opposite end as represented at 19, and the external diameter of the member 9 is preferably equal to the internal diameter of the larger portion of the part 16, or slightly greater than the latter, these parts being provided for the telescoping of the upper end of the member 9, with the portion 16 of the member 8, in which position, the upper end of the portion 9, preferably abuts the annular shoulder 18. Any suitable means may be provided for releasably securing together the parts 8 and 9, it being preferred, however, that such means be so constructed that the parts will become automatically locked together upon the act of telescoping them as stated. Means of this character are shown in the drawings and comprise lugs 20 and 21 struck inwardly from the metal of the portion 16 at diametrically opposed points thereon to extend into openings 22 and 23 respectively in the portion 9 and interlock with the upper walls 24 and 25 respectively of these openings, these lugs automatically locking with the parts as stated upon the act of telescoping the members 8 and 9, the upper wall of the latter flexing sufficiently to allow of the telescoping of the parts 8 and 9 to the position stated.

Any suitable interior structure for electrical connection with the wires 12 and 13 and for receiving an electric bulb and supply current thereto, may be provided.

As the structure is shown, and preferably provided, the above-referred-to interior structure involves switch mechanism controlling the supply of current to the electric lamp referred to, the switch mechanism being accessible for operation at the member 9, the particular switch mechanism shown being of the pull-chain type, the chain extending exterior of the member 9 and being operatively connected with the switch parts. The interior construction referred to, which, as to its general features, is of well known construction, involves a lower porcelain disk 26 and an upper porce-

lain disk 27 rigidly connected in spaced relation with co-operating switch members one of which is represented at 28 and is rotatably mounted, this member being connected with a pull-chain 29 which extends through a hollow guide member 30 located in the slot 19 of the member 9. Surmounting, and secured to, the porcelain disk 27 is a ring 31 of metal from which rises, at opposite sides thereof, metal bars 32 connected therewith in any desirable way, as by soldering them thereto, the upper ends of the bars 32 being electrically connected in any suitable way, as for example by soldering, to a screw-shell 33, such as commonly employed in electric-socket structures, the center contact 33^a of this shell being electrically connected, as by soldering, to the upper end of a wire 34 (as shown in Fig. 2^a).
 10 The ring 31 is electrically connected with a binding post 100 of the switch device, to which the wire 13 is connected, the other binding post 101 of this switch and to which the wire 12 is connected, being electrically connected with the lower end of the wire 34. The opening and closing of the circuit in which the bars 32, wire 34 and shell are interposed, may be effected by successive pulls on the chain 29 in a well known manner.
 15 Surrounding the wire 34, bars 32 and shell 33 and fitting over the ring 31, is a tube 35 of any desirable material, such as paper, there being, by preference, cement, non-conductive of electric current and of any suitable kind, introduced into the tube to the position shown at 32^a, at the ends thereof, to embed the bars 32 and wire 34 and firmly secure the tube and the parts surrounded therein, and hold the current-conducting members, with which it engages, firmly in position.

Surrounding the tube 35 is a candle tube 36 which may be made of any suitable material as for example paper, or cardboard, with its exterior preferably of glossy finish to resemble a candle, the tube 36 extending at its lower end into, and closely fitting, the reduced portion 17 of the member 8 and seating upon the upper edge of a lining 37 of insulating material interposed between the socket-portion 9 and the switch-portion of the structure hereinbefore described and containing a slot 37^a in registration with the slot 19.

In assembling the parts the switch-device with the superposed parts connected therewith as stated, and with the wires 12 and 13 connected to certain parts as stated is introduced into the lining 37, the latter having been first placed in the socket member 9, in which position the guide 30 assumes the position in the socket 9, as illustrated. The section 8 is then slipped over the tube 35 and forced over the upper end of the section 9 to the position shown in

which the lugs 20 and 21 become interlocked with the upper surfaces 24 and 25 of the apertures 22 and 23 in the section 9 and the shoulder 18 extends over the upper edge of the member 37. The tube 36 is then telescoped with the tube 35 to the position shown in Fig. 2.

It will be understood from the foregoing that not only may a candle-socket structure be readily and economically made in accordance with my invention, but the several parts are rigidly held together in assembled condition.

While I have illustrated and described a particular construction embodying my invention, it will be understood that the same may be variously modified and altered without departing from the invention.

What I claim as new, and desire to secure by Letters Patent, is:

1. In a device of the character described, a switch assembly, an inner tube permanently assembled therewith, a supporting cup member enclosing said switch assembly, a locking ring member interlocking with said cup member, one of said members having a slot, a portion of said switch projecting through said slot and retained by coaction of said members, and an outer, candle, tube freely slidable on said inner tube and telescoping with said ring.

2. In a device of the character described a base comprising engaged members one of which has a slot, a switch enclosed in said base having a portion projecting through said slot and retained by the other member, one of said members flaring outwardly from its junction with the other member, a ring like flange on one of said members having a reduced portion to provide a shoulder, a cup of insulating material in said base about said switch and engaging with said shoulder and a candle tube telescoping with said flange and rising from said base.

3. In a device of the character described a base comprising a cup having a slot, a switch in said cup having operating means projecting through said slot, an upwardly concaved annular ring, a flange about the opening in said ring telescoping with the sides of the cup and retaining said switch operating means in said slot, a tube extending above said base, a supporting strip of conducting material rising from said switch within the tube, a lamp socket carried by said supporting means, a conductor for the central contact of said socket and initially plastic material in said tube contacting the latter and maintaining the relation of parts.

4. In a device of the character described, a unitary structure comprising, in combination, a switch assembly, a socket for a lamp disposed above said switch and connections therebetween, a sectional casing separate from said unitary structure and in which

said switch is located and containing an opening in its wall through which a portion of said switch projects, said unitary structure being held in position by the sections 5 of said casing and a candle tube extending above said sections and in which said unitary structure is located, and slideable into place after the other parts above recited are assembled.

10 5. In a device of the character described, a unitary structure comprising a switch assembly, a socket for a lamp disposed above said switch, connections therebetween, and a tube extending from said switch to said 15 socket and surrounding said connections, a sectional casing separate from said unitary structure and in which said switch is located and containing an opening in its wall through which a portion of said switch projects, said unitary structure being held in position by the sections of said casing, and a candle tube extending above said sections and in which said unitary structure is located, and slideable into place after the other 20 parts above recited are assembled.

25 6. In a device of the character described, a switch assembly, an inner tube permanently assembled therewith and extending upwardly therefrom, a supporting cup member enclosing said switch assembly, a locking ring member interlocking with said cup member, one of said members having a slot, a portion of said switch projecting through said slot and retained by coaction 30 of said members, and an outer, candle, tube freely slideable on said inner tube and telescoping with said ring.

7. In a device of the character set forth, the combination of a base, a tube rising from said base, contacts at the upper end of said tube including a screw shell, conductors in said tube and connected with said contacts, binding posts on said base and connected with said conductors and initially plastic material in the lower end of said tube and 40 contacting said base and operating to stiffen said tube and hold said tube and base together.

8. In a device of the character set forth, the combination of a base comprising a 50 switch device, a tube rising from said base, contacts at the upper end of said tube including a screw shell, conductors in said tube and connected with said contacts, binding posts connected with the switch elements of 55 said switch device, said switch device being connected with said conductors, and initially plastic material in the lower end of said tube and contacting said base and operating to stiffen said tube and hold said tube and 60 base together.

9. In a device of the character described, the combination of a unitary structure comprising a base, a socket for a lamp disposed 65 on said base, connectors between said base and lamp, and a tube extending from said base to said socket, a supporting member for said unitary structure, and a candle tube extending above said supporting member and 70 slideable into a position in which it surrounds the other parts recited, after such other parts are assembled.

MAX HERSKOVITZ.
